CLOSURE PLUG AND METHOD OF FORMING
SAMERichard L. Parish, Chicago, Ill., assignor to
American Flange & Manufacturing Company,
Chicago, Ill., a corporation of Illinois

Application May 13, 1932, Serial No. 611,067

8 Claims. (Cl. 29—148.2)

My invention relates to closure plugs and method of forming same, and it has to do more particularly with a plug well adapted for closure of the openings in metallic containers suited for transportation and storage of oil, gasoline, and the like.

One of the objects of my invention is to provide an improved, simple, inexpensive and light weight, yet highly efficient and durable, closure plug formed of sheet metal.

A further object is to provide from a single piece of sheet metal a plug having an externally threaded, cup-shaped body, an exterior gasket-receiving and supporting surface, a head with a seal seat thereon, and lug means integral with the body and formed therein in the shaping of the sheet metal for facilitating insertion and removal of the plug from the opening which it is adapted to close.

Another object is to provide a novel and inexpensive method of forming a plug of the foregoing character, the same being carried out in such a manner as to condense, thicken and strengthen the wall of the completed plug sufficient to accommodate the finishing operations and to withstand the conditions of use to which it may be subjected.

Other objects and advantages will become apparent as this description progresses and by reference to the drawings wherein,—

Figure 1 is a perspective view of a blank from which the body of the plug may be formed;

Fig. 2 is a vertical sectional view of die structure (diagrammatically shown) illustrating the initial forming of the blank of Fig. 1 into a cup shape;

Fig. 3 is a perspective view of the cup formed by the die of Fig. 2;

Fig. 4 is a vertical sectional view of die structure, illustrating a preliminary forming operation on the cup of Fig. 3;

Fig. 5 is a section taken substantially on line 5—5 of Fig. 4;

Fig. 6 is an elevational view of the cup after its preliminary forming by the die of Fig. 4;

Fig. 7 is a vertical sectional view of a final-forming die, illustrating in vertical section the cup formed thereby;

Fig. 8 is a section taken substantially on line 8—8 of Fig. 7;

Fig. 9 is a vertical sectional view of the finally-formed cup, taken at right angles to the section of the cup shown in Fig. 7;

Fig. 10 is a top plan view of the blank of Fig. 9,

illustrating an object (in section) applied thereto for rotation thereof; and

Fig. 11 is an elevational view, partially in section, of the finished plug.

In general, the steps involved in making a plug according to my invention include the forming of a single cylindrical blank of sheet metal of desired size into a cup-shaped blank of greater depth than the finished plug. This cup blank is then acted upon by a die suitably shaped to strike or punch the side wall of the cup radially inward at diametrically opposed points to initially form opposed hollow lugs projecting within the cup body; and during this same operation I preliminarily compress the side wall of the cup in axial direction, reducing somewhat its height and increasing slightly the thickness of its side wall. The cup blank thus treated is then subjected to the action of a final-forming die to further compress its side wall in axial direction, thereby further compacting and thickening the cup side wall to the desired extent for threading and final finishing of the plug. During this final forming operation, the inwardly projecting lugs initially pressed from the side wall of the cup are finally shaped to provide finished lugs which may be engaged by a suitable tool (such as a monkey-wrench, screw driver, bar of metal, etc.), inserted within the finished plug for screwing the same into or out of the opening it is adapted to close. After the cup body has been formed as last stated, it is finally finished to form the completed plug by externally threading the same and by shaping the upper exterior part thereof above the threads to provide a gasket receiving space and a head having a seal seat surface.

In the drawings, I have illustrated the foregoing steps of my invention together with one form of structure which may be employed in carrying out the same. Specifically, a preformed cylindrical blank 15 (Fig. 1) is formed into a cup 16 (Fig. 3) by die structure which may take the form of male and female die members 17 and 18, respectively (Fig. 2).

The preformed cup 16 is next acted upon by the die structure which may take the form shown in Fig. 4. Specifically, the cup blank is inserted (with its bottom downward) in a female die member 19 which is provided with a pair of internal, diametrically opposed punch members 20 which project inwardly into the die cavity 21, which die members 20 have their upper surfaces, preferably, rounded as at 22. After the cup 16 is inserted in the die member 19, it is then engaged and pressed inwardly by a male die member 23. This

latter die member is provided with a head portion 24 having a reduced portion 25 depending therefrom providing a shoulder 26 which engages the upper rim of the cup blank. This die member 23 is also provided in its reduced portion 25 with diametrically opposed recesses 27 adapted to align with the die punch members 29, which recesses are of enlarged dimensions adapted to freely receive the punch members 29 and the cup wall material forced thereinto by such punch members. In the use of this die structure (Fig. 4), as the die member 23 is moved inwardly with the cup 16, the female punch members 29 strike or punch the side wall of the cup into the male die recesses 27 forming preliminary indentations in the side wall of the blank and providing inwardly projecting, hollow and diametrically-opposed lugs 28, of a shape best shown in Figs. 4 and 6. During this operation, the side wall of the cup 20 is slightly compressed axially and is slightly thickened thereby reducing the height of the same as clearly shown in Figs. 4 and 6.

The cup blank 16 is, preferably, finally completed by a die structure such as that illustrated in Fig. 7. More particularly, this die structure includes a female die member 29 having a cylindrical, unobstructed cavity 30, in which the preformed cup blank of Fig. 6 is adapted to be seated. The preformed blank is then acted upon by a male die member 31 which is provided with a head 32 and a reduced depending shank portion 33 having diametrically opposed recesses 34 adapted to align with and receive the preliminarily-formed hollow lugs 28. With this structure, as the male die member 31 is moved inwardly, the shoulder 35 thereof formed by its portions 32 and 33 engages the top of the blank rim with the lugs 28 received in its recesses 34, and as this movement is continued the side wall of the cup 40 is compressed axially and compacted to further and finally thicken the same as shown in Fig. 7. As this action takes place, the metal forming the lugs 28 is bowed and flowed somewhat further inwardly and the top portions of these lugs are 45 flattened so that they finally take the shape shown in Figs. 7 to 10, inclusive. It will be noted that the height of the cup wall has been reduced so that the top portions of the lugs 28 extend approximately flush with the top edge of the cup, 50 and that the lugs so formed take substantially a wedge-shape in horizontal section (Figs. 8 and 10). It will be further noted that the finished lugs 28 are so shaped and related that an object, such as a bar of metal 36 as illustrated in Fig. 55 10, inserted within the plug body will seat against opposite sides of opposed lugs at the bases of the lugs so that a firm and secure engagement is insured and great pressure may be applied to the bar 36 to rotate the plug body without danger of 60 distortion and injury to the plug body and lugs.

After the plug blanks has been finished to the extent shown in Figs. 7, 8, 9 and 10, it is then finally finished by externally threading the same as at 37 and by cutting away its top part at an 65 angle to provide a head 38 having an angular seat surface 39. The threads 37 extend only part way to the angular seat 39 leaving a smooth, annular gasket-receiving and supporting surface 40.

The advantages of my invention first above stated will be obvious from the foregoing. A simple and inexpensive plug formed of sheet metal is provided. The plug is of a single piece construction and is light in weight, which is a material 75 factor with respect to shipping expense. Fur-

thermore, a plug formed in accordance with my invention is strong and durable and capable of withstanding the usage and handling to which plugs of this character are ordinarily subjected.

I claim:

1. A closure plug formed entirely from a single piece of sheet metal which comprises a cup-shaped body having the lower part of its outer side wall threaded, a head having an angled seat surface formed at the top of the outer side wall of said body, said head being spaced from said threaded portion to provide a gasket-receiving space, the side wall of said body having diametrically-opposed, inward indentations triangularly-shaped in cross-section providing internal lugs adapted to be engaged by a suitable tool to rotate the plug.

2. The method of forming a sheet metal closure plug having a cup-shaped body which comprises the steps of shaping a preformed cylindrical flat blank of sheet metal of uniform thickness into the form of a cup of substantially uniform diameter, striking the side wall of the cup radially inward at diametrically opposed points below the upper or free edge of the cup and simultaneously compressing the side wall of the cup in axial direction, thereafter additionally compressing the cup side wall in axial direction to finally compact and thicken the same and simultaneously and finally shaping the inwardly struck portions to provide inwardly-extending lugs triangularly shaped in cross-section within the finished plug, and externally threading the outer wall of the cup.

3. The method of forming a sheet metal closure plug which comprises the steps of shaping a preformed, cylindrical flat blank into the form of a cup of greater depth than the finished plug, striking the side wall of the cup radially inward at a plurality of points to provide triangularly-shaped lugs within the cup, compressing the cup side wall in axial direction to thicken the same and to bring it to the finished depth of the plug, and finally externally threading the compressed side wall.

4. The method of forming a sheet metal closure plug which comprises the steps of shaping a preformed, cylindrical flat blank into the form of a cup of greater depth than the finished plug, simultaneously compressing the side wall of the cup in axial direction and striking the side wall inwardly at a plurality of points, finally compressing said side wall to the depth of the finished plug and simultaneously and finally shaping said inwardly-struck portions to provide lugs for insertion and removal of the plug, and finishing the plug by externally threading its outer side wall and shaping its side wall above its threaded part to form a head spaced from said threads by a gasket receiving space.

5. In a closure plug formed from a single piece of sheet metal, a cup-shaped body having its lower outer portion threaded, a head of substantially the same diameter as said threaded portion provided at the upper end of said body and spaced from said threaded portion, the outer edge of said head being shaped to provide an inclined gasket seat, and diametrically-opposed lugs triangularly-shaped in cross-section struck inwardly from said side wall at a point spaced below said head.

6. In a closure plug formed of a single piece of sheet metal of uniform thickness, a cup-shaped body having its side wall thickened and the lower outer portion of said side wall threaded, a head formed on the upper part of said body within the diametrical limits of said threaded portion and

spaced from said threaded portion, and diametrically opposed lugs triangularly-shaped in cross-section that are formed from the material of said side wall and which project inwardly toward each other from said side wall to be engaged by a tool for applying the plug to or removing it from a threaded opening.

7. A closure plug formed entirely from a single piece of sheet metal which comprises a cup-shaped body having the lower part of its outer side wall threaded, a head having a seat surface formed at the top of the outer side wall of said body, said head being spaced from said threaded portion to provide a gasket-receiving space, the side wall of said body having diametrically-op-

posed, inward indentations providing internal lugs adapted to be engaged by a suitable tool to rotate the plug.

8. The method of forming a sheet metal closure plug which comprises the steps of shaping a pre-formed, cylindrical flat blank into the form of a cup of greater depth than the finished plug, striking the wall of the cup radially inward at a plurality of points to provide lugs within the cup, compressing the cup side wall in axial direction 19 to thicken the same and to bring it to the finished depth of the plug, and finally externally thread-
ing the compressed side wall.
